UNITED STATES PATENT OFFICE.

FERDINAND PIENING, OF RENDSBURG, GERMANY.

DOOR-LOCK.

No. 872,582.

Specification of Letters Patent.

Patented Dec. 3, 1907.

Application filed December 17, 1906. Serial No. 348,190.

To all whom it may concern:

Be it known that I, FERDINAND PIENING, a subject of the Emperor of Germany, residing at Rendsburg, Germany, have invented 5 a new and useful Door-Lock which can be Closed, of which the following is a specification.

The object of my present invention relates to door locks closed by means of a lock arranged inside the bolt.

In the accompanying drawings, in which I have illustrated my invention, like letters of reference refer to like parts throughout the different views.

15 In said drawings, Figure 1 shows a door bolt closed by a padlock. Fig. 2 shows a door bolt closed by a lock arranged inside said bolt. Fig. 3 shows detail views of the handle and its connection rod to the bolt. 20 Fig. 4 shows detail views of the mechanism for arresting the bolt. Fig. 5 shows detail views of the bolt. Fig. 6 shows a plate for fastening the device to a door.

The door lock as shown in Fig. 1 is chiefly 25 used on doors to be opened from the outside such as used for closets, soldiers' wardrobes and the like.

a illustrates a handle on which a square formed connection rod b is fixed. The rod 30 b is rounded off at c. A prolongation of the rod b is formed by a pin d to which the square rod e designed to receive the bolt is firmly attached. The outer end of the square rod e is provided with a screw thread f which together with the screw g serves to hold fast 35 the bolt. Below the rod b I arrange the plate like stop h providing a hole i. The mechanism for the arresting of the bolt, as shown in detail in Fig. 4, consists of a plate k 40 providing a square edged bar l terminating into a screw threaded part m. The plate k provides a hole o. The bolt p (Fig. 5) has a quadrangular hole q for the pin e.

The whole mechanism is fastened to plates 45 r (see Fig. 6) fixed to the door. These plates provide two holes s and t the circular one s serving to receive the bolt d, while the quadrangular one t serves to receive the square edged bar l. The fitting together of the single parts and the operation of the bolts is as described hereafter.

The plates r are fixed to both sides of the door in such a manner, that the circular

holes are above the square edged holes. The pin d is passed into the circular holes. Now 55 the bolt p is fixed by means of the thread f and the screw g. The square edged bar l is passed through the lower holes t of the plates r in such a manner that the plate k with its hole o is directed to the top. The plate k is 60 held fast by means of the thread m and the screw n.

If the bolt shall be closed the handle a is turned so far until the stop h rests against the plate k in such a way that the holes i and 65 o cover each other. Now a padlock is passed through said openings. The bolt p is so mounted upon the square edged part e that it catches in this position behind the molding of the closet and thereby prevents 70 an opening of its door. If the door shall be opened I first take off the padlock and then turn the handle a of the bolt 90 degrees.

If my improved device shall be used for house-doors or corridor-doors I locate the 75 bolt p not behind but between the plates r (Fig. 2). The handle u placed on the outside of the door is in this case provided with an internal thread v by means of which it is screwed upon the thread f of the inner handle. In this manner the bolt p is connected 80 with the outer handle as well as with the inner handle. Here I prefer to leave away the padlock and instead of the same mount a lock in the plate k the closing part of which 85 fits into a slit of the rod b preventing a turning of the rod as well as a turning of the bolt.

What I claim as new and desire to secure by a United States Letters Patent is:—

1. In a door lock the combination of a 90 handle, a plate like stop (h) fixed to one side of said handle, a plate fixed below said handle, and means to place the stop (h) against the plate (k) if the bolt is locked substantially as and for the purpose set forth. 95

2. In a door lock the combination of a handle, a plate like stop (h) fixed to one side of said handle, a hole (i) provided in said plate like stop, a plate fixed below said handle, a hole (o) provided in said plate, means 100 to locate the holes in such a manner that they cover themselves if the handle is turned, means to place the stop (h) against the plate (k), and a means for locking the parts together substantially as and for the purpose 105 set forth.

3. In a door lock the combination of two handles, means to screw one handle into the other, a slit provided in a bar (b), of one handle a plate (k), a lock located in said plate 5 and means to prevent a turning of the handles and bolt substantially as set forth.

In witness whereof I have hereunto signed

my name, in the presence of two subscribing witnesses.

FERDINAND PIENING.
